UNITED STATES PATENT OFFICE

135,540

DESIGN FOR A PORTABLE RADIO DEVICE

Donald H. Mitchell, Chicago, Ill., assignor to Galvin Manufacturing Corporation, Chicago, Ill., a corporation of Illinois

Application February 23, 1942, Serial No. 105,951

Term of patent 14 years

To all whom it may concern:

Be it known that I, Donald H. Mitchell, a citizen of the United States, residing at Chicago, in the county of Cook and State of Illinois, have invented a new, original, and ornamental Design for a Portable Radio Device, of which the following is a specification, reference being had to the accompanying drawings, forming part thereof, in which:

Fig. 1 is a side perspective view of a portable radio device showing my new design;

Fig. 2 is an enlarged side view of the side shown in Fig. 1;

Fig. 3 is an elevational view of the back thereof;

Fig. 4 is a top plan view thereof; and

Fig. 5 is a bottom plan view thereof.

The characteristic features of my new design are shown in solid lines in the drawings.

I claim:

The ornamental design for a portable radio device, substantially as shown and described.

DONALD H. MITCHELL.
